INVENTOR
ROY E. LANGMACK
ATTORNEY

UNITED STATES PATENT OFFICE.

ROY E. LANGMACK, OF MINNEAPOLIS, MINNESOTA.

LUBRICATING MECHANISM.

Application filed July 5, 1927. Serial No. 203,519.

This invention relates to lubricating devices for internal combustion engines, and the primary object is to provide means of a novel, practical and efficient nature for lubricating the upper portion of each piston of the engine, which portion of the piston usually contacts with the cylinder walls in a relatively dry state, because of the piston rings which prevent the splash fed oil from reaching this area of the piston and cylinders. The objections and difficulties resulting from the lack of proper lubrication in this comparatively dry region are many, and among them may be mentioned the following: "slapping" of the piston; hard starting, due to the increased friction; burning of the cylinder walls, due to dry condition; premature wearing out of piston rings and uneven wear on cylinder walls, requiring early replacement of new rings and regrinding of cylinders, etc. A further object is to provide means for automatically starting or opening this lubricating system, at any predetermined speed of the motor, so that the pistons will only receive the additional lubricant when most needed, and not when operating at slow speeds; at which time the normal or usual splash feed, from the crank case, may be sufficient. Further and more specific objects will be disclosed in the course of the following specification, reference being had to the accompanying drawing, in which:

Fig. 1 is a side elevation of a conventional gasoline engine, such as used in motor vehicles, which incorporates my invention.

Fig. 2 is a sectional plan view, about as on the line 2—2 in Fig. 1, but with various parts omitted.

Fig. 3 is an enlarged sectional elevation about as on the line 3—3 in Fig. 1.

Fig. 4 is a detail plan view, partly in section, of the control and indicating unit employed in the system.

Fig. 5 is a plan elevation of the unit as shown in Fig. 4.

Fig. 6 as a sectional detail view on the line 6—6 in Fig. 4.

Referring to the drawing more particularly and by reference characters A designates an internal combustion engine, having a series of cylinders B, in which reciprocate pistons C, connected to the crank shaft D by piston rods E, all of common and well known construction. The usual method of lubri-

cating the contacting areas of the pistons and cylinders is to provide the crank case with a body of oil, which is thrown by the cranks of the shaft up into the cylinders, and to prevent oil from seeping up past the pistons, which would result in fouling of the spark plugs, poor compression, and faulty ignition, it is also customary and necessary to provide the pistons with rings, such as F. And as to this construction, I have no changes to make, in view of the universal acceptance and use thereof in practically all motor cars. But, notwithstanding the popularity and efficiency of this type of engine, it does have the serious objections above noted, and in order to eliminate these defects, I provide a force feed method of lubricating the aforesaid dry area, and the same will now be set forth in detail.

A pipe 4 extends down into a low point of the crank case or oil pan of the engine and is provided or connected with a pump, indicated by dotted lines 6 in Fig. 1, which has for its function to draw oil into the pipe, from the oil reservoir, and pumping it up into the pipe 4.

The pipe section 4^a extends up to the usual oil gage (not shown), but has a T-coupling 4^b, which is connected by a short pipe 4^c to a valve shell or cylinder 4^d, secured as by bracket 4^e to the engine A. The shell 4^d has an outlet connection 4^f, with which may be connected (as shown in Fig. 1) a pipe 4^g leading to the second oil gage, if desired. The pipe 4^f is connected with a loop pipe 7, which encircles the engine, and which has discharge pipe 8, provided with a valve 9, for returning the unused oil to the reservoir in the crank case. The cylinders B communicate with opposite pipes of the loop 7, through nipples or short connections 10, whereby the oil may be conducted from the pipes 7 to the interior of the cylinders.

It may here be noted that the connections 10 are so located in the cylinder walls B that they will never be uncovered by the pistons, and thus the pressure in the loop 7 will always remain substantially constant, when the valve unit 4^d is open, as in Fig. 6. And when each piston is in its lowermost position, as shown in Fig. 3, the oil ducts 10 will be close to the upper end of the piston, and will have been traversed by the piston rings F as well as the upper portion of the piston.

The valve 4^d controls the supply and pres-

sure of oil to the ducts 10, and the valve 9, while shown as an ordinary hand valve, may be a pressure, reducing or automatic valve, which by being properly adjusted will control and regulate the supply and pressure of the discharged or return oil, and thus by being adjusted with respect to the valve 4^a will permit a very sensitive oil feed adjustment to be had.

10 The valve shell 4^a has a pair of diametrically opposed ducts 11, which communicate with the pipes 4^c and 4^f. A core or piston 12 is rotatably carried in the shell and has a shaft 13 which projects out through the head 14 and has a crank arm 15 at its outer end. This arm is connected by a link bar 16 to the speed adjusting arm 17 of the carburetor 18 of the motor. Thus, when the accelerator bar 19 is moved, to open the gas 20 valve, it will also move the bar 16 to turn the valve piston 12. This piston has a pair of opposed peripheral channels 20, connected by a diametrical hole 21, thus forming a substantially Z-shaped conduit for connecting 25 the ducts 11. The position of the piston 12 with respect to the arm 15 may be adjusted in any suitable manner, as by a set screw 22, and the position of the piston is indicated by a pointer 23, which is mounted so that it can 30 be read with respect to a scale 24. This scale is conveniently marked with graduations of 0 to 60, indicating the miles per hour at which it is desired to have the oil to start feeding. Thus, if the device is set 35 with the pointer at 30, as in Fig. 5, when the engine is not running, then when it is running at a speed of thirty miles per hour or more the feed will be effected, as any speed over that set will keep the channels 20 in 40 communication with the ducts 11. It will be understood that the reason for this predetermined range of operation is that there is little or no need for this feed when the engine is running at slow speeds, at which times the customary splash feed is sufficient, 45 in itself, to lubricate the pistons.

It is understood that suitable modifications may be made in the general design and structural details of the invention as herein shown and described, provided, however, that said modifications come within the spirit and scope of the appended claims.

Having now therefore fully shown and

described my invention, what I claim to be new and desire to protect by Letters Patent 55 is:

1. The combination with an internal combustion engine having a carburetor, a cylinder and a piston in the cylinder, of means for adjusting the carburetor to control the speed of the engine, a conduit adapted to contain oil under pressure and communicating with the cylinder at a point where it will conduct a lubricant to the upper peripheral surface of the piston, a valve in the conduit, means adjustable simultaneously with the carburetor adjusting means for opening the conduit valve upon a predetermined adjustment of the carburetor, and means for regulating the valve adjusting means whereby the valve may be caused to open at any selected predetermined speed of the engine as determined by the carburetor adjusting means.

2. The combination with an internal combustion engine having a carburetor, a cylinder and a piston in the cylinder, of means for adjusting the carburetor to control the speed of the engine, a conduit adapted to contain oil under pressure and communicating with the cylinder at a point where it will conduct a lubricant to the upper peripheral surface of the piston, a valve in the conduit, and means adjustable simultaneously with the carburetor adjusting means for opening the conduit valve after a predetermined adjustment of the carburetor has first been effected, said valve adjusting means having a scale for indicating the approximate engine speed, at which it will open when in operation, as determined by the carburetor adjusting means.

3. The combination with an internal combustion engine having a series of cylinders, of a conduit having ducts communicating with the cylinders, said conduit being circuitously connected with the oil reservoir of the engine, a valve having a rotatable core for controlling the flow of oil through the conduit and to said ducts, and an actuator member for oscillating the core, and means for adjusting the operative position of the core with respect to the actuator member.

In testimony whereof I affix my signature.

ROY E. LANGMACK.
